LOCK FOR DETACHABLE STRAP HANDLES

William Castedello and Walter G. Lohmeyer, Jr.,
Stamford, Conn., assignors to The Kalart Company Inc., Stamford, Conn.

Application August 2, 1946, Serial No. 638,043

5 Claims. (Cl. 24—265)

1

This invention relates to locks, particularly to locks for securing a strap to an item.

One object of the invention is a novel and improved lock of the general type, above referred to, by means of which a strap can be fastened to and removed from an item.

Another object of the invention is a novel and improved strap lock which can be fastened to and removed from an item without requiring the loosening of any parts or the use of tools.

Another object of the invention is a novel and improved strap lock which, when placed in its locked position, is automatically secured therein.

Another object of the invention is a novel and improved strap lock which can be unlocked by exerting a pressure against the locking parts of the lock.

Other and further objects, features and advantages of the invention will appear hereinafter and be pointed out in the appended claims forming part of the invention.

In the accompanying drawings, a now preferred embodiment of the invention is shown by way of illustration and not by way of limitation.

Fig. 1 is an elevational side view of a strap with a lock according to the invention.

Fig. 2 shows a plan view of the strap and lock fastened to the casing of a camera, the casing being shown partially broken away.

Fig. 3 is a detailed top view of the lock according to the invention.

Fig. 4 is a side view of one side of the lock according to Fig. 3.

Fig. 5 is a side view of the opposite side of the lock according to Fig. 3, and

Fig. 6 shows a plan view of a lock according to the invention in application to a wrist watch.

Referring now to the figures in detail.

Figs. 1 and 2 show a strap 10 made of leather, fabric, plastic or any other suitable material. At each end of the strap, there are provided loops 11 and 12 respectively which serve to fasten locks according to the invention, generally designated 13, to the strap. Each lock comprises two cross pins 14 and 15 which are joined by side bars 16 and 17. Cross pins 15 are passed through loops 11 and 12 respectively, which are secured by rivets 18 and 19 respectively. Side bar 17 is fastened to cross pins 14 and 15 by any suitable means, such as rivets 20 and 21, as can best be seen in Fig. 3. Side bar 16 is pivotally fastened to cross pin 15 by any suitable means, such as a rivet 22 and is provided at its distal end with an open slot 23. This slot is designed and positioned to engage a neck portion 24 of cross pin 14, as

2

can be best seen on Fig. 3. There is further provided a leaf spring 25 partially fastened to side bar 17 and having at its free end an eyelet 26 through which cross pin 14 is passed. The free end of leaf spring 25 is biased to assume normally the position shown in Fig. 3. It should be noted in this connection that instead of a leaf spring 25, any other suitable spring means may be employed.

10 Let it now be assumed that the strap and lock, as shown, is to be used as handle, and that it is desired to fasten the handle to a casing 30 of a photographic apparatus such as a camera (part of a camera casing is diagrammatically shown 15 on Fig. 2). Then, side bar 16 is lifted and cross pin 14 is inserted in a sleeve 31 fastened by any suitable means, such as a bracket 32 and rivets 33 to camera casing 30. By exerting a pressure against side bar 17 leaf spring 25 is flattened, as 20 shown in Fig. 2 and side bar 16 is again slipped over neck portion 24. The action of spring 25 will press side bar 16 against a rivet head 34 at the outer end of neck portion 24, thereby holding the lock in its closed position. In order to 25 secure the lock, a recess 35 is provided in side bar 16 into which recess rivet head 34 is pressed by the action of spring 25 when the lock is closed.

When it is desired to remove the handle, side bar 16 is pressed inwardly, that is, toward side bar 17 until recess 35 clears rivet head 34, whereupon side bar 16 is swung upwardly so that cross pin 14 can be withdrawn from sleeve 31.

In the previous description, reference has been made to the use of the strap and the lock as a handle for photographic cameras. However, it 35 should be understood that a lock and strap according to the invention can be used for various other purposes, such as a handle for carrying cases, luggage, bags, suit cases, brief cases and other suitable items requiring use of a handle. The lock according to the invention can further be used in connection with the strap of a wrist watch, for instance, to fasten a strap to the watch and to remove it quickly and conveniently therefrom. Furthermore, lock and strap according to the invention can be advantageously employed to secure a watch to the wrist and to take off the watch.

Fig. 6 shows an arrangement in which a lock 50 according to the invention is employed to fasten the strap of a wrist watch to the watch casing.

As will be apparent from an examination of Fig. 6, the pins conventionally provided at a watch casing for the purpose of securing the two portions of a watch strap correspond to the pins

15 of a lock as shown on Fig. 3. The two portions 35 and 36 of a conventional strap are fastened to lock pins 14 by slipping loops 35' and 36' respectively, of the strap portions over lock pins 14. The strap portions are secured by means of springs 25 and can be removed by lifting side bars 16 of the lock as has been previously described.

The use of a lock according to the invention to fasten a watch strap to a watch casing has the particular advantage that the watch strap can be easily replaced by the wearer of the watch without requiring the services of a watch maker. Furthermore, the lock can be made of the same material as the watch casing, thereby improving the ornamental appearance of the watch.

It will be understood that it is also possible to fasten the lock to the strap portions themselves. Then lock pins 15 will be passed through loops 35' and 36' respectively, and lock pins 14 will be at the watch casing proper.

While the invention has been described in detail with respect to a certain now preferred example and embodiment of the invention it will be understood by those skilled in the art after understanding the invention, that various changes and modifications may be made without departing from the spirit and scope of the invention and it is intended therefore, to cover all such changes and modifications in the appended claims.

What is claimed as new and desired to be secured by Letters Patent is:

1. A lock of the type described for releasably locking together two members, said lock comprising a pair of cross pins, each of said cross pins being arranged to be connected with one of the two members to be locked together, a first side bar fastened at each end to one of said cross pins, a second side bar pivotally connected at one end to one of the cross pins and having an open slot at the other end arranged to receive the second cross pin, said second cross pin having an enlarged head portion protruding beyond the pivotal side bar when the second cross pin is received in the slot, and spring means associated with the second cross pin for urging the pivotal side bar against the said head portion when one of said members is fastened to the second cross pin between the spring means and the pivotal side bar, thereby securing the pivotal side bar to the second cross pin.

2. A strap lock for releasable attachment to a strap having a loop on one end, said lock comprising a pair of cross pins, one of said cross pins being arranged to receive said strap loop, a first side bar fastened at each end to one of said cross pins, a second side bar pivotally connected at one end to one of the cross pins and having an open slot at the other end arranged to receive the

second cross pin, and spring means supported on the lock and positioned to press the loop portion of the strap toward and against the pivotal side bar when the second cross pin is received in the slot.

3. A strap lock as described in claim 2, wherein said second cross pin has an enlarged head portion protruding beyond the pivotal side bar when the second cross pin is received in the slot, thereby securing the pivotal side bar to the second cross pin in response to the pressure of the loop portion of the strap against the pivotal side bar.

4. A lock of the type described for releasably connecting two members, comprising a pair of cross pins, each of said cross pins being arranged to be connected with one of the two members to be locked together, a first side bar fastened at each end to one of said cross pins, a second side bar pivotally connected at one end to one of the cross pins and having an open slot at the other end arranged to receive the second cross pin, and a leaf spring fastened at one end to the first side bar and encompassing the second cross pin, said spring being biased into a position spaced from the first side bar for urging the pivotal side bar against the second cross pin when one of the members is fastened to the second cross pin between the biased spring and the pivotal side bar.

5. A lock as described in claim 4, wherein the second side bar has a recess adjacent to said slot, and wherein the second cross pin has a neck portion positioned to engage the slot of said second side bar and a head portion arranged to engage said recess when the slot of the second side bar is engaged by said neck portion, thereby locking the second side bar to the second cross pin.
